UNITED STATES PATENT OFFICE.

ORANGE O. OZIAS, OF DAYTON, OHIO.

DESIGN FOR A COMPUTING MEMBER FOR SCALES.

SPECIFICATION forming part of Design No. 27,641, dated September 14, 1897.

Application filed July 19, 1897. Serial No. 645,180. Term of patent 14 years.

To all whom it may concern:

- Be it known that I, ORANGE O. OZIAS, of Dayton, in the county of Montgomery and State of Ohio, have produced a new and original Design for Computing Members for Even-Balance Scales, of which the following is a specification, reference being had to the accompanying drawings, forming a part of the same.
- 10 In said drawings, Figure 1 is a top plan view of a structure showing my present design, and Fig. 2 is an end elevation, these two views being deemed necessary to fully illustrate my design.
- 15 The leading feature of my design consists in a flat computing member having horizontal parallel rows of graduations on its flat face with arms or brackets extending backwardly from a central point at each of its ends and
- 20 a rear member between the arms.

A indicates the graduated computing member, which is flat or has its opposite faces substantially plane surfaces, and B B are the arms or brackets. These arms or brackets extend from opposite ends of the member A 25 rearwardly and are connected by a rear member C. The rear member C has three projections c on each side, as shown, and the member A has a series of horizontal graduations arranged in parallel rows. 30

What I claim is—

The design for computing members for even-balance scales having the flat body with parallel horizontal rows of graduations, rearwardly-projecting end arms and rear member, as set forth. 35

ORANGE O. OZIAS.
